Crosby & Gould.

UNITED STATES PATENT OFFICE.

CHARLES W. GLIDDEN, OF LYNN, MASSACHUSETTS.

IMPROVEMENT IN LASTING-MACHINES.

Specification forming part of Letters Patent No. 140,265, dated June 24, 1873; application filed May 6, 1873.

To all whom it may concern:

Be it known that I, CHARLES W. GLIDDEN, of Lynn, in the county of Essex and State of Massachusetts, have invented an Improved Lasting-Machine; and I do hereby declare that the following, taken in connection with the drawings which accompany and form part of this specification is a description of my invention sufficient to enable those skilled in the art to practice it.

The invention has particular reference to that class of lasting-machines employing flexible sacks or bags for receiving the upper and last and pressing the edges of the upper beyond the face of the last, water or other fluid being forced into the bag to expand it against the upper, the invention being, however, more or less applicable to other lasting-machines.

In my invention I combine with the matrix or box that receives the last and upper a reciprocating slide having a nail-tube, which, by the advance of the slide, is carried over the edge of the upper (pressed over the last by the end of the advancing slide) and under a driver having a downward movement that drives the nail, the retreat of the slide preferably bringing the tube under a nail-supplying tube, from which the nail drops or is forced into the nail-tube of the slide.

My invention consists in such an organization and in details of construction and arrangement of mechanism pertaining thereto.

The drawing represents a machine embodying my invention. Figure 1 shows the machine in side and sectional elevation. Fig. 2 is a plan of it. Fig. 3 is a front view, the last-supporting mechanism being removed.

a denotes a bed-plate having a pedestal, *b*, in the upper part of which is mounted the upper-crimping and nail-tube slide and the nail-supplying and driving mechanism. *c* denotes a pin or support pivoted to the front end of a weighted lever, *d*, and having mounted upon it a yoke, *e*, to the two arms of which is pivoted the box *f* that receives the last and upper, the last being preferably supported upon pins *g* extending through the box, and from an arm, *h*, forming part of the box-frame. When this box is to contain the flexible bag, (or a flexible lining with a fluid space behind it) suitable inlet and discharge tubes are provided for injecting the fluid into the bag and

permitting it to escape therefrom, as in other machines using such bags. The top plate *j* of the box is in or nearly in the plane of the top of the last, and beyond the rim *i* is a flange, *k*, forming, with the rim *i*, a groove, *a²*, into which extends a guide-roll, *l*, or a pin projecting from the head *m*, the rim *i* being pressed up against the roll by rolls *p*, or pins extending from slides *n*, that slide in the head and are forced forward by springs *o*. The projecting part of the box under the groove rests upon a button, *q*, which button extends from a vertical slide, *r*, that is pivoted to a foot-lever, *s*, pressure upon the outer end of the lever lifting the slide and button and the button holding the flange up to the crimper and nail-tube slide. *t* denotes the crimper and nail-tube slide, moving horizontally in the head, *m* and having at its rear end a slot, *u*, and rolls *v*, through which slot and between the rolls a vertical bar, *w*, passes. This bar is jointed at its lower end to a link, *x*, pivoted to a foot-lever, *y*, and has on opposite sides inclines *z*, one of which, as the bar is raised by the lever, presses forward the crimper-slide *t*, and the other, as the bar falls, drawing back said crimper-bar. In the front end of the crimper-slide is a nail-tube, *a²*, which, when the slide is drawn back, is directly under a tube, *b²*, through which the nails or nail-wire passes into the tube, and as the slide moves forward this tube with its nail is brought under a driver, *c²*, and over the edge of the upper, which, by the movement of the crimper-slide, is pressed over the edge of the inner sole laid upon the last. This driver slides vertically in a bearing at the front of the head *m*, and is connected to the front arm of a lever, *d²*, whose rear arm extends over the bar *w*. As the bar rises the tube charged with a nail is driven forward, and when the nail-charged tube has reached a position directly under the driver the bar strikes the lever, forcing down the driver *c²* through the tube, and driving the nail or tack into the upper and inner sole to fasten them together. When the slide *t* retreats the driver *c²* is forced up by a suitable spring, *e²*.

If a continuous wire be used to form the nails the forward movement of the slide may serve to sever the nail from the wire.

I claim—

1. In combination with mechanism for receiving the upper and last a crimper-slide, t , operated by the inclines z on the bar w , substantially as shown and described.
2. In combination with the crimper-slide t , the nail-tube a^2 and nail-driver c^2 , arranged and operating substantially as shown and described.
3. In combination with the crimper-slide t , nail-tube a^2 , and driver c^2 , the supply-tube b^2 .
4. In combination with the crimper-slide, the box f , supported and pivoted substantially as shown, and made with the groove x^2 and flange k , the guide-pin or roll l entering the groove, the pins or rolls p pressing against the roll l , and the button q pressing the flange k up to the pin, all substantially as shown and described.
5. In combination with the crimper-slide t , and with the driver c^2 , the bar w for imparting the forward and back movements to the slide and the downward movement to the driver, substantially as described.

C. W. GLIDDEN.
